Duluth, Minn., a corporation of Minnesota

Application November 9, 1949, Serial No. 5,956

Term of patent 14 years

(Cl. D49—1)

To all whom it may concern:

Be it known that I, Myron L. Gaster, a citizen of the United States of America, residing at Duluth, in the county of St. Louis and State of Minnesota, have invented a new, original, and ornamental Design for a Line Holder, of which the following is a specification, reference being had to the accompanying drawing, forming a part thereof.

In the drawing:

Fig. 1 is a side elevational view of a line holder, showing my new design.

Fig. 2 is a similar view showing the holding cam in release position.

Fig. 3 is a front elevational view of my holder as shown in Fig. 1.

Fig. 4 is a top plan view of Fig. 2.

I claim:

The ornamental design for a line holder, as shown.

MYRON L. GASTER.
